(57) **CLAIM**

The ornamental design for a smart glasses display panel with augmented reality graphical user interface, as shown and described.

DESCRIPTION

FIG. 1 is a front view of a first embodiment of the new design for a smart glasses display panel with augmented reality graphical user interface;

FIG. 2 is a front view of a second embodiment thereof; FIG. 3 is a front view of a third embodiment thereof; and, FIG. 4 is a front view of a fourth embodiment thereof.

The broken line showing of a portion of display panel is for the purpose of illustrating environment and forms no part of the claimed design. The broken line showing of elements on the display panel illustrate portions of the graphical user interface and form no part of the claimed design.

1 Claim, 4 Drawing Sheets
